UNITED STATES PATENT OFFICE.

SIDNEY BLUMENTHAL, OF NEW YORK, N. Y.

DESIGN FOR PILE FABRIC.

SPECIFICATION forming part of Design No. 30,749, dated May 9, 1899.

Application filed March 9, 1899. Serial No. 708,450. Term of patent 7 years.

To all whom it may concern:

Be it known that I, SIDNEY BLUMENTHAL, a citizen of the United States, and a resident of New York, in the county and State of New York, have invented and produced a new and original Design for Pile Fabrics, of which the following is a specification, reference being had to the accompanying drawing, forming a part thereof.

The leading features of my design consist in a pile fabric presenting a body portion, a selvage, and a narrow band composed of contrasted sections or portions extending along the body portion in proximity to the selvage and distinguished from the body portion and selvage.

In the accompanying drawing, A represents the body portion of the fabric, B represents the selvage, and C represents the band composed of contrasted sections or portions.

25

What I claim is—

The design for pile fabrics substantially as shown and described.

In testimony that I claim the foregoing as my invention I have signed my name, in presence of two witnesses, this 6th day of February, 1899.

SIDNEY BLUMENTHAL.
